MACHINE FOR THE AUTOMATIC PACKING
OF SHUTTLES AND SUCH LIKE TOOLS
INTO CASESAntonio Scotti, Schio, Vicenza, Italy; vested in
the Alien Property CustodianApplication October 8, 1938, Serial No. 234,011
In Germany October 21, 1937

5 Claims. (Cl. 226—14)

It has heretofore been the custom in spinning mills to pack by hand shuttles and similar tools for shipping purposes. This packaging is a very troublesome and tiring task which absorbed a long time.

The object of this invention is to provide a machine for packing shuttles automatically and speedily. This object is accomplished by introducing the shuttles and similar tools into a conveying apparatus by means of which they are carried to a collecting machine which reciprocates in a vertical direction, and which, after having been lowered, opens automatically releasing the row of shuttles contained therein. A reversing control device may be provided to cause the automatic return of the collecting apparatus to its original position.

Should every layer of shuttles to be packed consist of several rows arranged one after another, it will be necessary to put the case on a truck or a sledge that will have to shift every time one row of shuttles has been packed, the right number corresponding to their length.

The drawings illustrate how this invention is carried out, viz:

Fig. 1 is a side view of the machine embodying the invention,

Fig. 2 is an end elevation of the collecting apparatus with its propelling organs in its superior position seen from one end,

Fig. 3 is an end elevation of the collecting apparatus in its lowered position,

Fig. 4 is a view similar to Figure 3 taken from the side,

Fig. 5 a perspective view of the device for moving the truck,

Fig. 6 is a detailed view of a mechanism for controlling the movement of the truck, and

Fig. 7 is a diagrammatic view of the electric circuit.

For the working of shaft 1, upon which a conical coupling 2 is arranged an electric motor A which may be engaged or disengaged by hand by means of a switch is employed. A second electric motor B, operated by means of pressure buttons b, b, and a relay 21, controls the upward and downward movement of the collecting apparatus 5. A third motor C drives an endless conveyor belt 3, as well as the ejector device 4 and the truck 16. Motor C is controlled by means of a pressure button c through a relay 18 (see Fig. 7). It will be noticed from Figure 1 that the ejector device 4 is driven by the motor C through the intermediary of the driv-

ing belts shown in dotted lines and the rollers 51.

The shuttles are put by hand between tape-trailers 3 and pushed by the action of ejector device 4 into the collecting apparatus when the latter is in its upper position, as shown in Figure 1. The collecting apparatus is fork shaped and is reciprocated by means of a lifting pulley 4a in a vertical direction. The collecting apparatus is provided at each side with gripping members 6 which are held in gripping position by means of the helical spring 8 which is mounted on the pivot pin for the gripping members. The gripping members are shown gripping shuttle 1 in Figures 2 and 3. When the gripping members abut against the bottom of the packing case, the pressure will spread them apart and thus the load will be released. They are held in their open position by means of spring-actuated pawls 6a. Below gathering apparatus 5—open on either side—upon the machine frame, is arranged a continuous tape 9 which revolves round an axle 15 and is supplied with abutting pieces 10 for disengaging a lever 11. The former are arranged upon tape 9 at a distance corresponding to the length of a full load. The fitting is arranged in such a way so that one of the abutting pieces 10 will always find itself before one of these loads as, owing to their pliability, the shuttles cannot disengage lever 11. The lever 11 acts like a latch during the carrying operation and as soon as it becomes disengaged from contact with the abutting pieces 10, the control rod 12 will also become disengaged. By means of a lever 13 this controlling rod provokes conical coupling 2 to fall into gear, more exactly through the action of a spring 14. Consequently control shaft 1 is caused to revolve by motor A, and through the action of lever 1a and the crank 1b, tape 9 will swing about axle 15 to assume the position not shown and which will leave the collecting apparatus 5 free below. At the same time tape 9—when turning downwards—continues its movement by the action of a gear just far enough to carry the next abutting piece 10 before the opening of the collecting apparatus 5. The next movement of device 10 and that of the tape, until lever 11 is disengaged, occurs at intervals under the influence of the shuttles put into the collecting apparatus 5.

The disengagement of the rod 12 cuts off the relays 18 and 17 from the electric circuit. This results in stoppage of the motor C, the conveyor belt 3 as well as the ejector device 4 and the

truck 16. The immediate stop is obtained by means of an electro-magnetic brake 22. By the short rotation of control shaft 1, as above described, and a cam 19, switch 20 of relay 21 is closed and motor B switched on so collecting apparatus 5 is now pushed downwards under the thrust of a toothed rod 31 which, in turn, is actuated by the gear 31a. By lowering the collecting apparatus upon the bottom of case 24, or the load contained therein, it opens automatically by the spreading of the gripping members 6 under influence of pin 6b and the spring 6c, while the shuttles push up a double-bottomed plate 32. The open position of gripping members 6 is effectuated by means of latches 6a. The lower portion of plate 32 is movable or yieldable, in order to obtain a certain play should the thickness of the shuttles be different.

In their disengaged position gripping members 6 are held by means of latches 6a. In this way the rows of shuttles contained in the collecting apparatus are freed and discharged. Moreover by lowering the collecting apparatus, an organ supplied with a pressure pin 27 is shifted axially by means of a coupling operated by motor B within gear-box 26. Thus the latter organ, in contrast with the action of a spring, can be pushed against a piece—now still—of the coupling, owing to the arrangement of slanting surfaces or a wedge or by means of a screw (not shown in the drawings). Pressure pin 27 pushes a switch 23 bringing into play an inversion of the poles of motor B by means of a relay 21. The motor will thus revolve in an opposite direction and raise the collecting apparatus 5 once more upwards to its former position. Shortly before reaching such a position motor B is automatically disengaged by means of an abutting piece 28 and a switch 29. At the same time controlling rod 12 is pushed back, while a projection 34 arranged on a toothed rod 31 strikes upon a roller 33 dis-

placing the same, by the action of conical-shaped surfaces, towards the right side, in such a way that the projection at the end of controlling shaft 12 engages with that of lever 11. Thus one obtains once more the initial position illustrated in Fig. 1. Upon the falling into gear of pieces 11 and 12, the conically-shaped coupling 2 is again thrown into gear by shaft 13. Thereupon controlling shaft 1 is set into motion and provokes the return of continuous tape 9 in the position illustrated in full lines in Fig. 2. At the same time, by means of cam 35, switch 36 is closed and by this also the circuit of electric motor C then carrying-tape 3, ejector device 4 and the means for operating truck 16 and put into action once more.

In case of emergency the movement of the collecting apparatus can be manually reversed by the actuation of the button switch b.

Box 24 is fitted upon truck 16 with suitable means. The truck runs with its wheels on guides 37 and bears on one side a support 38 on which are arranged some rollers 39 which serve as abutting pieces. The latter serve to control the movement of the truck. As soon as collecting apparatus 5 has returned to its upper position in the manner above described, upon the revolving movement thus produced, control shaft 1 within lever arms 41 and 42 is moved by means of a hoisting pulley 40. In this operation the prolongation 43 of lever 42 pushes spring-latch 44 aside. The latter frees lever 45 submitted to the action of the spring 45a. At the very same time, by means of a second projection 46 of lever 42, a

driving organ 47 bearing a spring, kept still in this position by lever 45 supplied with catch 48 (see Fig. 6), is pushed forward. Within a V-shaped notch of organ 47 a double lever 49 falls into gear and is shifted either to the right or to the left by the movement of the aforesaid organ, according to the position of a sliding block 50. The latter is pushed, in the final position of truck 16, by means of adjustable abutting pieces 51 of support 38 in both directions, so that one of the springs 52 is stretched while the other is loose. Owing to this stretched spring 52 the same will pull lever 49, by the movement of organ 47, into that side of the V-shaped notch whereon the stretched spring can be found.

According to the direction of its movement, double lever 49 will cause either one or the other of the two couplings 53 and 54 to fall into gear and shaft 55—operated by motor C by means of a chain movement 59—can put into action shaft 58 through gears 56 or 57 in either direction. By means of a screw-controlled device 60 shaft 58 will cause a rope pulley 61 to revolve which results in the rope being wound and unwound, according to the direction of rotation, one of the two ends of rope 62, thus pulling the truck in the corresponding direction. This movement is governed by means of rollers 39 arranged upon their support 38 at distances corresponding to the length of the shuttles. As soon as the truck has covered such a distance then the next roller 39 pushes the sliding block supplied at its inferior end with conical surfaces in contrast with the action of a spring, upwards and falls into gear again with its projection 44 upon latch 45. In this way projection 48 is unhooked. Now it is possible to withdraw organ 47 by the action of the spring causing lever 49 to go back to its vertical position by means of the V-shaped notch in organ 47 (see Fig. 5) provoking the unclutching of the truck control.

When the last roller but one 39 of truck 16 begins to move, either one or the other of the abutting pieces 63 arranged upon support 38, pushes down the corresponding button 64 provoking at the same time the lighting of a red or a yellow lamp. This luminous signal will tell the workman that one layer of shuttles in the packing case is complete. In consideration of the conical shape of the shuttles, in order to avoid empty spaces, the next layer must be arranged in a contrary way upon carrying tape 3.

At the end of the truck movement for a layer of shuttles, a spring latch 66 is raised by the abutting piece 65 in such a way that the sliding block 50 upon engagement of abutting piece 51 with the abutting piece 61, is shifted and the lever 49 is reversed under the tension of the spring 52. It will be noted from Fig. 5 that the abutment members 67 are mounted resiliently in the block 50 through the provision of springs 67a. Upon the shifting of control rod 50 a pin 68 pushes down appendix 69 of checking-lever 45 thereby disengaging lever 45 itself. This device has the scope of giving the truck at the end of every movement (to lay down a layer) still a slight supplementary push so that the packing case, independently from the position of the shuttles put down last, may reach the exact final position.

Lever 70, in case of need, allows one to remove by hand lever 45, while a spring pressure pin 71 offers the possibility to operate by hand lever 49 for the coupling of the control means for the movement of the truck.

The present invention, besides the packing of the shuttles and such like tools, as above described, may be applied also for the packing of tubes and cartridges either full or empty of all types and dimensions, boxes of all types and dimensions, and so forth. For such a purpose it will suffice to suitably vary the pitch of the chain 3 (Fig. 1) and, where necessary, the opening of the grooved guides 6 in the gathering apparatus (Fig. 3).

What I claim and desire to secure by Letters Patent is:

1. A machine for the automatic packing of shuttles and similar objects in packing cases, said machine comprising a conveyor carrying the objects, a collecting box, an ejection device for pushing the objects from the conveyor into said collecting box, said collecting box having an endless band constituting the bottom of said collecting box; and rollers supporting said endless band; means moving said endless band longitudinally and operated by the pushing action of the objects introduced into the collecting box by the ejection device, a slideable truck supporting a packing case, and means connected with the said collecting box for depositing the objects from the collecting box into the packing case.

2. A machine for the automatic packing of shuttles and similar objects in packing cases, said machine comprising a conveyor carrying the objects, a collecting box, an ejection device for pushing the objects from the conveyor into said collecting box, said collecting box having an endless band constituting the bottom of said collecting box; and rollers supporting said endless band; means moving said endless band longitudinally and operated by the pushing action of the objects introduced into the collecting box by the ejection device, a member situated at a distance from said endless band and extending parallel thereto in a horizontal direction, and means operatively connecting said endless band with said member, and turning said endless band about said member when the collecting box is filled by a row of objects.

3. A machine for the automatic packing of shuttles and similar objects in packing cases, said machine comprising a conveyor carrying the objects, means connected with the conveyor for actuating the same, a collecting box, means connected with the collecting box for lowering the same, an ejection device for pushing the objects from the conveyor into said collecting box, means connected with said ejection device for actuating the same, said collecting box having an endless band constituting the bottom of said collecting box; means connected with said endless band for removing the same from said collecting box, two abutting pieces secured vertically to said endless band at a distance from one another, and means actuated by said abutting pieces to stop said conveyor-actuating means and said ejection device.

5 actuating means and to actuate said collecting box-lowering means and said endless band-removing means, said abutting pieces being operated by the pushing action of the objects introduced into said collecting box by the ejection device and actuating the stopping means when the collecting box is filled with a row of objects.

10 4. A machine for the automatic packing of shuttles and similar objects in packing cases, said machine comprising a conveyor carrying the objects, means connected with the conveyor for actuating the same, a collecting box, means connected with the collecting box for lowering the same, an ejection device for pushing the objects from the conveyor into said collecting box, means connected with said ejection device for actuating the same, said collecting box having an endless band constituting the bottom of said collecting box; means connected with said endless band for removing the same from said collecting box and for returning it back to said collecting box, means connected with said endless band-removing means for moving said endless band longitudinally, two abutting pieces secured vertically to said endless band at a distance from one another, and means actuated by said abutting pieces to stop said conveyor-actuating means and said ejection device and to actuate said collecting box-lowering means and said endless band-removing means, said abutting pieces being operated by the pushing action of the objects introduced into said collecting box by the ejection device and actuating the stopping means when the collecting box is filled with a row of objects.

15 30 35 40 45 50 55 60 5 A machine for the automatic packing of shuttles and similar objects in packing cases, said machine comprising a conveyor carrying the objects, a collecting box, an ejection device for pushing the objects from the conveyor into said collecting box, said collecting box having an endless band constituting the bottom of said collecting box, and a pair of oppositely disposed, pivoted gripping members adapted to engage a shuttle; means moving said endless band longitudinally and operated by the pushing action of the objects introduced into the collecting box by the ejection device, means connected with said collecting box for lowering the same to deposit the objects contained therein into a packing case and for raising the collecting box, the objects being held in position by the pressure of said gripping members when said endless band is moved longitudinally and means connected with said gripping members for maintaining them in an open position while said collecting box is moved downwardly to deposit the objects into said packing case and for closing said gripping members when said collecting box is moved into its uppermost initial position.

ANTONIO SCOTTI.
